UNITED STATES PATENT OFFICE.

HENRY J. PODLEŠÁK, OF CHICAGO, ILLINOIS, ASSIGNOR, BY MESNE ASSIGNMENTS, TO
INTERNATIONAL HARVESTER CORPORATION, A CORPORATION OF NEW JERSEY.

CARBURETER FOR GAS-ENGINES.

1,226,366.

Specification of Letters Patent.

Patented May 15, 1917.

Application filed January 6, 1913. Serial No. 740,479.

To all whom it may concern:

Be it known that I, HENRY J. PODLEŠÁK, a citizen of the United States, residing at Chicago, in the county of Cook and State 5 of Illinois, have invented certain new and useful Improvements in Carbureters for Gas-Engines, of which the following is a full, clear, and exact specification.

This invention relates to carbureters for 10 internal combustion engines, more generally known as gas engines.

In the operation of gas engines, it is of great importance that the fuel, whatever it may be, should be thoroughly vaporized 15 to produce the best working results. In cases where comparatively light fuel, such as gasolene, is used, the fuel vaporizes quite readily when the oil and air are mixed under ordinary atmospheric conditions. In 20 cases where a heavy hydrocarbon, such as kerosene, fuel oil, and heavy distillates, are used, more difficulty is experienced in vaporizing the oil when it is mixed with air. To render a comparatively heavy hydrocarbon, 25 such as kerosene, thoroughly vaporized before it passes into the combustion chamber of an engine, has been a problem confronting those who are operating engines using such heavier hydrocarbons as fuel.

It is the object of my present invention 30 to thoroughly vaporize the oil fuel, especially the heavier hydrocarbons, such as kerosene, before the same enters the combustion chamber of an engine.

This object is accomplished by heating 35 the mixture, kerosene or other hydrocarbon and air, in a preheater before said mixture enters the combustion chamber.

The invention is illustrated on the ac- 40 companying sheets of drawings, in which Figure 1 is a fragmentary end view of an internal combustion engine equipped with my invention;

Fig. 2 is a fragmentary side view of the 45 same;

Fig. 3 is a sectional view of my improved carbureter taken in the plane of line 3-3 of Fig. 1;

Fig. 4 is a sectional view of said carbureter taken in the plane of line 4-4 of Fig. 3;

Fig. 5 is a partial sectional view of one portion of the carbureter taken in the planes of the irregular line 5-5 of Fig. 3;

Fig. 6 is a sectional view of the mixing

chamber taken in the plane of line 6-6 of Fig. 4;

Fig. 7 is a sectional view of the same taken in the plane of line 7-7 of Fig. 6;

Fig. 8 is a side elevation of the exhaust 60 gas chamber of the carbureter, the heating chamber being removed; and,

Fig. 9 is a view looking into the interior 65 of the heater portion of the carbureter wherein the fuel is thoroughly vaporized and mixed with air.

The various novel features of my invention 70 will be apparent from the description and drawings and will be particularly pointed out in the appended claims.

My invention is illustrated in connection 75 with a gas engine having a cylinder 10 to the end head 11 of which is secured my improved carbureter 12, including a casting 13 having a passageway 14 through which fuel is adapted to flow, and a passageway 15 through which water is adapted to flow, said passageways being separated by a partition 16. These two passageways 14 and 15 eventually terminate in a single passageway or mixing chamber 17 where the fuel, air and water mix preparatory to passing into the combustion chamber of the engine. Mounted on top of the casting 13 is a conduit 18 through which air may pass into the passageways 14 and 15. Secured to one side of the casting 13 is a receptacle 19 having a fuel reservoir 20 and a water reservoir 21. The fuel reservoir is supplied with fuel from any desired source through an inlet pipe 22, the pressure of the fuel being maintained constant within said fuel reservoir due to the fact that the latter is provided with an overflow having an outlet 23. In like manner, the water reservoir is provided with an inlet pipe 24 and an overflow 25. Fuel and water are adapted to be drawn up and out through their corresponding nozzles 26 and 27 upon the occurrence 80 of every inhalation stroke of the gas engine. The fuel nozzle 26 is provided with a manually controlled needle valve 28, and the water nozzle 27 is also provided with a like manually controlled needle valve 29.

Mounted upon a stem 30 passing through 105 the casting 13 are oil controlling valve 31 and water controlling valve 32 located in the passageways 14 and 15 respectively. The water nozzle 27 enters the air passage- 110 way 15 at a point somewhat higher than the

fuel nozzle 26 enters the passageway 14, and the valves 31 and 32 are mounted on the horizontal stem 30 in a manner such that when the water controlling valve 32 is closed, no water can pass down through the passageway 15, while at the same time more or less fuel can be drawn from the fuel nozzle.

The casting is mounted upon another casting 33 having an irregular passageway 34 registering with the exhaust pipe 35 of the gas engine, so that exhaust gases from the combustion chamber of the engine can pass through the irregular passageway 34, heating the walls, such as 36 and 37, of the casting 33, the exhaust gases then passing out through the pipe 38. This casting 33 is also provided with a set of passageways 39 and 39^a, the former registering with the fuel passageway 14 and with one end 40^a of an irregular passageway 40 in a removable heater or member 41 which is normally secured to the side of the casting 33. The other passageway 39^a registers with the other end 40^b of the irregular passageway 40.

This heater 41 receives its heat by conduction directly from the wall 37 of the casting 33. The heat is conducted through laterally extending lugs or projections 42 and a central partition 44 which are formed integrally with the three-sided wall 43 of the heater 41 so that all parts of the heater 41 become extremely hot. These lugs 42 are located in the irregular passageway 40 of the heater 41 to assist in thoroughly mixing the fuel, such as kerosene and air. At the same time the heated walls and lugs of the heater give up their heat to the mixture of fuel oil and air passing therethrough, causing the fuel oil to thoroughly vaporize before passing from the heater. The central partition 44 of the heater 41 forms the irregular passageway 40 and is also provided with extensions 45 which also assist in causing the air and fuel in said heater to thoroughly mix and vaporize. After the heated mixture passes through the heater 41, it is mixed with the water from the water passageway 15 in the passageway 17 which registers with a pipe 16, in which is located a throttle valve 17 mounted on a stem 18.

Secured to the valve stems 30 and 48 are arms 49 and 50 respectively connected by a link 51, the arm 50 being connected through link 52, arm 53, governor shaft 54 to a speed governor, not shown. The governor shaft 54 is suitably supported in a bracket 55.

When the engine is at a stand-still, the fuel controlling valve 31, water controlling valve 32, and throttle valve 17 are full open. The engine may be started either on gasoline or on a relatively heavy hydrocarbon, such as kerosene. If it is desired to start the engine on gasoline, the same may be injected into the fuel passageway 14, the gasoline

vaporizing when mixed with air. If, however, it is desired to start the engine on kerosene or some other heavy hydrocarbon, heat should be applied to the heater 41 by some means, such as a torch for instance, so that the heavy hydrocarbon fuel oil will be thoroughly vaporized upon passing through said heater. Of course when the engine is once started the exhaust gases, as explained, raise the temperature of the heater to an extremely high value for vaporizing purposes. To start the engine, the water is completely shut off by the needle valve 29, air freely flowing down through passageway 14, passing the fuel supply nozzle 26, and drawing therefrom a charge of the fuel oil. This inrush of air and consequent charge of fuel oil flowing through the passageway 14 is caused by the inhalation stroke of the piston of the engine. After passing the fuel nozzle 26, the fuel laden air flows through passageway 39^a and through the irregular passageway 40 of the heater 41, where the fuel, such as kerosene and air are thoroughly mixed and heated, the fuel therein being thoroughly vaporized. From the heater the vaporized fuel passes through passageway 39^a into passageway or mixing chamber 17, past the throttling valve 17, and into the combustion chamber where it is compressed and ignited resulting in its expansion for doing work. By thus heating the fuel and thoroughly vaporizing it in the heater member or preheater 41, as it may be called, the fuel is thoroughly vaporized previous to the time it enters the combustion chamber, thereby preventing any waste of the fuel. After about ten minutes when the cylinder of the engine is heated, the water is turned on and adjusted through the agency of needle valve 29, so that the proper amount can flow to mix with the vaporized fuel after the latter has passed through the preheater, the water and vaporized fuel then mixing in the passageway or mixing chamber 17, which is the termination of the water conduit 15 on one side and the combined passageways 14, 39, 40, and 39^a on the fuel side of the carburetor. After the vaporized fuel and water have mixed in the passageway 17, all of the ingredients of the explosive mixture are drawn into the combustion chamber. The purpose of mixing water with the explosive fuel mixture is to render the fuel comparatively lean and to prevent pre-ignition of the explosive mixture. Under normal full load speed conditions, the valves are all full open. If now the load decreases, the speed of the engine will increase and by means of the speed governor all of the valves will be moved toward closed position, thereby causing a decrease in the supply of air, fuel and water. At friction load the water controlling valve 32 is closed, preventing the admission of water and the fuel controlling

valve is partly closed so as to reduce the volume of air passing therethrough, causing a proportionate decrease in the supply of fuel, it being necessary that the explosive mixture be of a richer quality when the engine is working at friction load, at which time there is low compression.

In gas engines using gasoline for fuel, it is not ordinarily necessary to preheat the gasoline and air mixture previous to the time it enters the combustion chamber. However, in the cases of gas engines using the heavier hydrocarbon oils for fuel, such as kerosene, it is necessary to thoroughly 10 vaporize the kerosene mixture previous to the time it enters the combustion chamber for the purpose of running the engine at its highest efficiency and preventing loss of fuel, the fuel, if not completely vaporized, 15 ordinarily leaking past the piston. By the use of my preheater, all heavy hydrocarbon oils used as fuels can be thoroughly vaporized previous to the time they enter the combustion chamber of internal combustion 20 engines, thereby making it possible for an engine to operate at the highest efficiency and preventing the loss of fuel. If any fuel oil should collect in the bottom of the preheater before the engine has had an opportunity to warm up in starting, such fuel oil can be drained from the preheater by 25 withdrawing a plug 58 in the bottom of the preheater.

In this particular case I have shown my preheater as heated by the exhaust gases coming from the combustion chamber. However, where oil, instead of water, is used for cooling the engine cylinder, the oil, after having been heated in the cylinder 30 jacket can be utilized to heat the mixture of fuel oil and air passing through the heater instead of utilizing the exhaust gases for that purpose.

There may be various modifications and 35 arrangements of my invention other than that herein specifically illustrated and de-

scribed, and it is my intention to cover all such arrangements and modifications which do not depart from the spirit and scope of my invention as set forth in the appended 50 claims.

What I claim as new is:

1. In a carbureter, the combination of a member having two parallel passageways side by side, one for air and fuel, the other 55 for air and water, and means for heating the mixture of air and fuel before the same is mixed with the air and water from the second passageway.

2. In a carbureter, the combination of a 60 member having two associated parallel passageways side by side, one for air and fuel, the other for air and water, and a heater having a passageway forming a continuation of the air and fuel passageway. 65

3. In a carbureter, the combination of a member having two parallel passageways side by side, one for air and fuel; the other for air and water; a mixing chamber, and a heater intermediate said air and fuel passageway and said mixing chamber in which the mixture of air and fuel is heated before 70 mixing with the mixture of air and water from the second passageway.

4. In a carbureter, the combination of a 75 member having two passageways side by side, means for supplying fuel and air to one of said passageways and water and air to the other, an independent exhaust member through which hot fluid passes, and 80 means detachably secured to said member adapted to absorb heat therefrom and impart it to the fuel and air passing therethrough for vaporizing the fuel and air mixture before being mixed with said water. 85

Chicago, Ill., Dec. 17, 1912.

In testimony whereof I affix my signature, in the presence of two witnesses.
